UNITED STATES PATENT OFFICE

HOWARD W. PARTLOW, OF UTICA, NEW YORK

AUTOMATIC FIRE EXTINGUISHER

Application filed August 31, 1928. Serial No. 303,231.

This invention relates to fire extinguishers, wherein the extinguishing medium consists of carbon dioxide, and the like, which when liberated smothers the fire by displacing the oxygen in the air. The invention relates especially to means for automatically releasing the carbon dioxide, the said means being operated by one or more distant actuators, which may be thermally or otherwise controlled.

The carbon dioxide is usually disposed in steel bottles or tanks in liquid state, the bottles being hermetically sealed and the liquid changing to gas when the seal is broken.

The primary object of my invention is to provide novel means for liberating the extinguishing gas during the incipient stages of fires, the said means comprising a gravitational member which operates an instrument, by which the sealing element, or a suitable portion of the bottle, may be punctured for effecting the free discharge of the gas. This releasing mechanism, hereinafter designated the gravity head, is arranged to be detachably mounted upon or adjacent the sealed end of the container, and consists of a relatively heavy weight or hammer which is movable relatively to the container, the weight being held in its elevated position ready to descend and perforate the container, by a series of novel parts which are operatively connected with a sensitive diaphragm, the said diaphragm being flexed by a sudden blast of air derived from one of the distant actuators that communicate with the gravity head, whenever the actuator responds to the action of its thermostat. A further object is to provide simple means for resetting the gravitational releasing member, and for indicating that the latter is so set. And a further object is to generally improve and simplify, as well as to render more positive and reliable automatic fire extinguishers of the non-portable class.

The various features and parts of the invention will be understood from the detailed description which follows, and by reference to the accompanying drawings, in which—

50 Figure 1 is a diagrammatic view of a fire

extinguishing system, showing a plural arrangement of the chemical tanks, releasing, and distant controlling mechanisms. Fig. 2 is a top-end view of one of the gravity heads. Fig. 3 is a bottom end view of the same. Fig. 4 is a sectional view of one of the distant controls or actuators, taken on line 4—4 of Fig. 8, the view being shown horizontally instead of vertically. Fig. 5 is a vertical section, taken on line 5—5 of Fig. 2, showing the gravitational releasing mechanism, and the charging and discharging valve detachably mounted upon a tank, the parts of the gravity head and valve being shown in the ready to operate positions. Fig. 6 is a broken vertical section of the same, showing the mechanism of the head operated for dropping the weight that depresses the gas releasing plunger. Fig. 7 is a detail view of the closure and weight supporting mechanism, taken in the direction of the short arrow in Fig. 5. And Fig. 8 is an elevational view of the distant control mechanism with its cover removed.

In the drawings, 2 represents a metallic bottle or tank that contains the carbon dioxide, or other extinguishing fluid, the bottle being closed except at its top, which is formed with an internally threaded neck 2', to receive the reduced threaded lower end 3' of a charging and releasing valve body 3. The body 3 is hollow throughout and communicates with the tank 2, by means of a pipe 2^a, which screws into the part 3', and preferably extends to the bottom of the tank. The body 3 is formed with an enlarged chamber 3^a, and a lateral discharge opening 3^b, to which may be connected a pipe, as 3^x (Fig. 1), to carry the extinguishing gas to distant parts of a building. The chamber 3^a is partially closed at its top by a valve member 4 having a threaded portion 4' that screws into the body. The member 4 is a hollow throughout, and its top end is fitted with a bushing 4^a. The reduced lower end of the member 4 is fitted with a gland nut 4^x, which clamps a relatively thin copper or other disc 5 to the bottom of the member, and beneath the disc is a packing 5', which rests upon an upwardly facing flange 3^c of

the body, and cooperates with the disc to prevent leakage or accidental discharge of the contents of the tank 2. Above the disc 5 the member 4 is formed with a transverse port or opening 4^b, by which the gas discharges into the chamber 3^a and thence into the pipe 3^x, after the disc 5 is punctured or destroyed. Within the hollow of member 4 is axially disposed a plunger 6, which reciprocates in the bushing 4^a. The top end of the plunger extends above the bushing 4^a, and is fitted with a head 6'. To the lower end of the plunger 6 is fitted a tube 6^a that extends downwardly past the port 4^b, its lower end, which normally approaches close to the disc 5, being formed angular and sharp, so that when the plunger is forced downwardly, as by a heavy quick blow, the tubular knife 6^a pierces the diaphragm 5, and the contents of the tank 2, which ordinarily has a pressure of fifty or more pounds per square inch, instantly discharges into the tube 6^a and escapes via radial windows or openings 6^c into the passage 4^b. A spring 6^d engages a flange 6^e of the plunger and tends to normally hold the plunger above and clear of the diaphragm 5 (see Fig. 5). The valve 3 may be transferred from one bottle to another, as the containers become 30 emptied.

8 represents the gravity head that cooperates with and is supported by the valve, and comprises a tubular body 8', which is arranged to align axially with the valve and the tank 2, the bottom end of the body being fitted with a ring-like cap 8^a, which is internally threaded for detachably securing the gravity head to a threaded portion 3^d of the body 3. This disposes the tops 40 of the bushings 4—4^a, as well as the head 6' of the plunger, within the tube 8'. The top end of the cylinder 8' is fitted with an enlarged concentric extension 8^b, which is open at both ends and supports a flange 45 closure 9, by which the top of the head 8 is practically sealed. The closure 9 is formed with an upwardly facing diaphragm chamber 9', and is surmounted by a disc 9^a which is also formed with a coinciding complementary chamber 9^b having an inlet opening 9^c, and between the disc and the closure is disposed a relatively sensitive diaphragm 10, which operates a plunger 10', the latter having a relatively broad disc-like 55 head that engages the diaphragm. A nipple 10^d communicates with the chamber 9^b for the admission of air or other fluid for flexing the diaphragm downwardly. The plunger 10' reciprocates in an opening in 60 the center of the closure 9, and its lower end engages the longer arm 12' of a lever 12, which is pivoted in a depending split lug 9^e, by a pin 9^f. The shorter arm 12^a of lever 12 comprises a tooth which is disposed in 65 the path of a rockable L-shaped lever 13,

one arm of the latter lever having a shoulder 13' which is engaged by the tooth 12^a, for preventing the rocking of lever 13, when the parts are in the positions shown in Fig. 5. The lever 13 is also pivoted in the lug 9^e, by a pin 13^a, and its longer arm 13^c extends inwardly beyond the lug and is engaged by and supports the free end of a latch 14 whose opposite end is pivoted in another split lug 9^x of the closure. For this purpose, the latch is formed with a tooth 14', which directly engages the arm 13^c (see Figs. 5 and 6). Below the tooth 14' the latch is formed with a lip 14^a, that projects beyond the tooth and engages the underside of the arm 13^c to swing lever 13 from the release to the lock position, as may be understood by consulting Figs. 5 and 6. The upward swing of the latch 14 effects the locking engagement of tooth 12^a with the shoulder 13'. Lever 12 carries a spring 12^c, which is constantly in contact with the top edge of the latch 14. This tends to resiliently hold the plunger 10' in engagement with the diaphragm 10 ready for the next 85 releasing operation. The latch 14 is cut-away, as at 14^b, to form a forked arm 14^c, and to provide a gap 14^d between the free end of said arm and the lip 14^a. 15 represents a relatively heavy cylindrical weight 95 which is arranged to reciprocate freely in the tubular body 8', the top of the weight being fitted with an axially alining pin 15', which is formed with a head 15^a. When the weight 15 is raised after an operation, the 100 head 15^a first enters the gap 14^d, and as this upward movement continues, it swings the latch and related parts from the release position of Fig. 6, to the lock position of Fig. 5, and causes the free end of the fork 14^c 105 to straddle the pin 15'. This disposes the head 15^a in the opening immediately above the fork, and as the fork is then positioned horizontally across the axis of the body 8', the weight is held in the elevated position 110 (see Fig. 5), until a blast of air or other force depresses the diaphragm 10 and trips the levers 12 and 13 for freeing the latch and permitting the gravitation of the weight 15. The descending weight 15, which 115 ordinarily weighs about ten pounds, strikes the head 6' of the plunger 6 a sufficiently heavy blow to cause the sharp lower end of the tube 6^a to puncture the diaphragm 5 and liberate the carbon dioxide gas from the 120 tank 2 to quench a fire. In order to prevent the heavy weight from battering and injuring the plunger and bushing 4^a, an inverted cup-shaped metal guard 8^e is disposed in the bottom of the body 8' and rests upon the 125 cap 8^a, to absorb the shock of the blow and to support the weight after the plunger sinks below the plane of the guard. The means for indicating that the weight 15 is set ready for any emergency, comprises a 130

rod 29 formed with a disc-head 29' that plays in a perforation in the closure 9. The lower end of this rod is flexibly connected to the latch 14 by a link 30, and is reciprocated by the raising and lowering of the latch. When the rod 29 projects well above the closure, as shown in Fig. 7, it indicates that the weight 15 is held suspended by the latch.

The weight supporting mechanism of the head 8, in the present case, is shown actuated by a distant control, which will now be briefly described: The mechanism of the distant control is supported by a base 16, which is arranged to receive a protecting casing 16'. Upon the base 16 is mounted a cylinder 17, having feet 17' secured to the base by screws 17^a. In practice, the control is disposed vertically, as shown in Figs. 1 and 8. The cylinder 17 is open at its top and closed at its bottom, the top being reduced, as at 17^b. 18 represents a plunger that slidably fits the bore of the cylinder, the top end thereof being fitted with a cylindrical weight 18', by 25 which the plunger is moved downwardly by gravity when released, for compressing the air in the body 17, and creating a sudden blast which escapes through a port 17^a, from which it is conducted by a pipe 19 to the 30 gravity head, or other device, for releasing the weight 15, as described. The top end of the plunger 18 is inserted in an axial bore 18^c of the weight, the said bore being enough larger than the plunger to admit the reduced 35 portion 17^b of the air cylinder when the weight descends. By this means a more compact arrangement of the control may be effected. The plunger 18 is held elevated, as shown in Figs. 4 and 8, by a pin 20, which 40 is formed with a round end 20' to facilitate the quick release of the plunger, when the locking pressure against the pin is relaxed, as when a fire starts. The pin 20 is held in the locking position by the short arm of a 45 bell-crank 21, which is pivoted in a split lug 16^c of the cylinder 16. The weight 18' is raised by a forked member 22, which is pivoted between the base and cover, and is fitted with an external hand-lever 22', by 50 which the member is manipulated. This forked member is normally held in its lowermost position shown in Figs. 4 and 8, by gravity, the arms 22^a of the yoke straddling the cylinder 17 and being disposed in the 55 path of the weight. The swinging upwardly of the lever 22', as shown in Fig. 1, raises the weight 18', and at the same time, the weight rocks an angular member 23, which is also pivoted to the base, for shooting the 60 pin 20 inwardly beneath the plunger. For this purpose, the member 23 is formed with an arm 23' which overlies the weight, and also with an arm 23^a that is normally in engagement with the short arm of bell- 65 crank 21, which in turn engages the head of

the pin 20. The lever 21 is arranged to rock in a vertical plane, as shown in Fig. 8, and said lever is tilted towards and held in the full line position, by the member 23, as long as the weight 18' is elevated. When the 70 several parts are operated as last described, an upright member, a sort of floating lever, as 24, moves inwardly beneath the long arm of lever 21, by the tension of a spring 25. This tends to hold the parts in the ready-to- 75 operate position, shown in Fig. 8. The member 24 is controlled by a thermostat comprising an expansible tube 26, which is rigidly secured in horizontal position below the casing 16', by a lug 16^d of the base. 80 Within the tube 26 is disposed a rod 27, one end of which extends through the lug 16^d and is fitted with a yoke 27'. The opposite end of the rod is fitted with a nut 27^a which engages the free end of the tube 26. The 85 turning of the nut in opposite directions moves the yoke towards and away from the lug and selectively determines the swing or movement of member 24 relatively to the long arm of lever 21. The heating and expanding (lengthening) of the tube 26, as by a quick rise of temperature of say from ten to thirty degrees in the space of one minute, owing to the adjustment of the rod 27, 90 effects the swaying of member 24, by means of a pair of dogs 28-28', which are pivoted within, but independently of the yoke 27', by screws 27^a. These dogs are bell-cranks, their short arms being in engagement with the yoke 27', while their long arms are disposed between and engage respectively pins 24' and 24^a carried by member 24. The pull 95 on the rod 27 by the lengthening of tube 26, spreads the long arms of the dogs 28 and effects the outward swing of the top end of member 24, for tripping or releasing the lever 21, which allows the weight 18' to 100 gravitate and compress the air in cylinder 17, as described. 105 Having thus described my invention, what I claim, is—

1. A latching mechanism for weight-actuated fire extinguishers wherein the weight has a headed supporting pin, including a support, a latch pivoted to the support and having a slot opening through its bottom to receive the pin and having a forked part to engage the head of the pin to support same, one end of the latch being free and having a tooth and a lip spaced from the tooth, a substantially L-shaped lever pivoted to the support and having one end thereof receivable in the space between the tooth and lip, a second lever pivoted to the support and having one end thereof engageable with the other end of the L-shaped lever to hold the latter against rocking, a spring connected to the second lever and engaging the latch, and thermostatically controlled means engaging the other end of the second 110 115 120 125 130

lever to actuate same thereby to actuate the L-shaped lever and therethrough to release the latch.

2. A latching mechanism for weight-actuated fire extinguishers wherein the weight

5 has a headed supporting pin, including a support, a latch pivoted at one end to the support and having a part between its ends to receive the pin and to engage the head thereof, a lever pivoted to the support, means on the opposite end of the latch to engage one of the ends of the lever, a second lever pivoted to the support and having one end engageable with the opposite end of the 10 first lever to hold the latter against movement, a spring between the latch and second lever to press outwardly against the opposite end of the latter, and heat controlled means engaging said opposite end of the second lever to actuate same and thereby the first lever and through the latter to release the latch.

3. A latching mechanism for weight actuated fire extinguishers, including means to 25 hold the weight in latched suspended position, heat-controlled means to release the latching means, and visual signal means operable by the latching means to indicate by its position resetting of the latching means.

30 4. A latching mechanism for fire extinguishers of the weight actuated type, including a pivoted latch having a free end provided with means to releasably support the weight, a pivoted device above the latch, means on the free end of said latch to engage one end of the device whereby the latter holds the latch in latched position, a normally horizontally disposed second device above the first device and having an 35 end engaged with the other end of the first end engaged with the other end of the first device to hold the latter against movement, a spring between the latch and the second device to press upwardly against the other end of the second device, and means to operate the other end of the second device thereby to operate the first device and through the latter to release the latch.

35 5. A latching mechanism for fire extinguishers of the weight actuated type, including a pivoted latch having a free end provided with means to releasably support the weight, a pivoted lever, adjacent the free end of the latch, means on the free end of said latch to engage one end of the lever whereby the latter holds the latch in latched position, a holding device above the latch and in register therewith and having an end engaged with the other end of the lever to hold the latter against movement, spring means 40 to hold the device in horizontal position, and means to operate the device thereby to release the latch.

6. A latching mechanism for fire extinguisher operators, including means to hold 45 the operator in latched position, a reciprocal

signal rod for indicating in one position resetting of the latching means and means to effect reciprocation of the rod by the movement of the latching means.

7. A latching mechanism for fire extinguisher operators, including means to hold the operator in latched position, visual signal means movable to different positions, and means operable by the latching means to move the signal means to a predetermined position so as to indicate by such predetermined position resetting of the latching means.

8. A latching mechanism including a releasable latch formed to be connected to the device to be latched, a movable device to engage the latch to hold same in latching position, a second movable device to hold the first named movable device in latching position, means to release the second named device, and a leaf spring between said second named device and the latch and connected to one of the same and bearing against the other, thereby to normally hold the second named device engaged with the releasing means.

9. A latching mechanism including a pivoted latch formed to be connected to the device to be latched, a pivoted device above the latch, means on the latch to engage the device so as to hold the latch in latched position, a second device above the first device having a part engaged with the first device to hold the latter latched, a spring between the latch and the second device and connected to one of the same and bearing against the other to press upwardly against the second device and means to actuate the second device thereby to operate the first device and through the latter to release the latch.

10. A latching mechanism including a releasable latch formed to be connected to the device to be latched, movable means to engage the latch to hold same in latching position, movable means to hold the first named movable means in latch engaging position, means to release the second named device having a part engaged therewith, and means between the latch and the second device and carried by one of the same and bearing against the other to urge the second device, upwardly.

In testimony whereof I affix my signature.
HOWARD W. PARTLOW.
